BOWL COVER OR THE LIKE

Nicholas D. Commisso, Victor, N.Y., assignor to Mobil Oil Corporation

Filed June 22, 1972, Ser. No. 265,381

Term of patent 14 years

Int. Cl. D9—07

U.S. Cl. D9—254

FIG. 1

FIG. 3

FIG. 1 is a top plan view of a bowl cover or the like showing my new design;

FIG. 2 is an elevational view; and

FIG. 3 is a cross-sectional view taken along line 3—3 of FIG. 1.

I claim:

The ornamental design for a bowl cover or the like, substantially as shown and described.
